UNITED STATES PATENT OFFICE.

HENRY SINGLETON-GRIESBACH, OF LIVERPOOL, ENGLAND.

SPARKING PLUG.

1,378,569.

Specification of Letters Patent. Patented May 17, 1921.

Application filed August 10, 1920. Serial No. 402,677.

To all whom it may concern:

Be it known that I, HENRY SINGLETON-GRIESBACH, a subject of the King of Great Britain, and residing at Cooper's Building, 5 Liverpool, Great Britain, have invented certain new and useful Improvements in and Relating to Sparking Plugs, of which the following is a full, clear, and exact description.

10 This invention relates to sparking plugs for the ignition of the charge within internal combustion engines and has for its object to provide an improved construction whereby the average temperature of the 15 plug shall be kept down to the lowest possible figure when in use.

For convenience in cleaning and renewal means are provided for complete dismantling of the components which means also 20 allow of adjustment being made to the spark gap when assembled.

It is proposed to provide the outer portion of a plug casing with cooling ribs and to retain the insulator by a perforated cap 25 screwing on the casing, the distinguishing feature being that such perforated cap covers such ribbed portion of the casing.

It is illustrated in the accompanying drawings Figures 1 and 2 which represent, 30 Fig. 1, a part sectional elevation and Fig. 2, a plan of the spark cap points. Referring to these it will be seen that the body A has a gilled upper portion F with a seat for the porcelain C, at S, such seat being a suitable 35 washer to give an effective seal, porcelain C is held in position and securely locked by cap B, which is suitably cut away as shown to give free access and circulation of air on to and around the gilled portion of body 40 F, and the base of porcelain C, the central electrode D, is secured to porcelain C, by the nut G, or may if desired be cemented in. The position of the sparking terminal of electrode D, corresponds to the arrow 45 marked on C, while the projection E, on the

base A, corresponds to the arrow shown on base at H. The position of D and E to one another can be recorded by the relative positions of arrows C and H also the indicator ring I.

The object of this construction is (1) to avoid any mass or body in contact with the engine cylinder (2) to conduct the heat therefrom by air in contact with the gilled trunk of the body and the cut away cap B, (3) to give free circulation of air around the base of porcelain (which is generally embedded in the body of the plug) (4) by suitable shape of electrode D, to conduct the heat from the point to the cool porcelain C, more rapidly than is possible in other plugs (5) to provide for the adjustment of the gap between the electrode and the body and to give instant accessibility to all parts for cleaning and replacing.

Modifications in construction to meet the above described requirements or variations will be obvious to those skilled in the art and can be effected without exceeding the scope of this invention.

Having now particularly described and ascertained the nature of my said invention and in what manner the same is to be performed I declare that what I claim is:

1. A spark plug comprising a hollow member provided with cooling fins, an electrode within said hollow member an insulator partially surrounding said electrode and seated on said hollow member, and a cap engaging said insulator and threaded to 75 said hollow member below the cooling fins.

2. The device of claim 1 in which the cap member is provided with cut away portions exposing the cooling fins.

In testimony whereof I have affixed my 85 signature in the presence of two witnesses.

H. SINGLETON-GRIESBACH.
